(57) **CLAIM**

The ornamental design for glasses with earphones, as shown and described.

DESCRIPTION

FIG. 1 is a front perspective view of glasses with earphones, showing an example environment;

FIG. 2 is a left-side view of the glasses with earphones of FIG. 1;

FIG. 3 is a right-side view of the glasses with earphones of FIG. 1;

FIG. 4 is a top plan view of the glasses with earphones of FIG. 1;

FIG. 5 is a bottom plan view of the glasses with earphones of FIG. 1;

FIG. 6 is a front view of the left glasses with earphones;

FIG. 7 is a perspective view of the left glasses with earphones of FIG. 6;

FIG. 8 is a second perspective view of the left glasses with earphones of FIG. 6;

FIG. 9 is a left-side view of the left glasses with earphones of FIG. 6;

FIG. 10 is a right-side view of the left glasses with earphones of FIG. 6;

FIG. 11 is a top plan view of the left glasses with earphones of FIG. 6; and,

FIG. 12 is bottom plan view of the left glasses with earphones of FIG. 6.

The dash-dot-dot-dash broken line immediately adjacent the solid-line portions of the design represents an unclaimed boundary of the design. The remainder of features shown in broken lines in FIGS. 1, 2, 3, 4, and 5, form no part of the claimed design.

1 Claim, 8 Drawing Sheets
